UNITED STATES PATENT OFFICE.

PHILIPPE DE CLAMECY, OF NEW YORK, N. Y., ASSIGNOR TO CORONA TYPEWRITER COMPANY, INC., OF GROTON, NEW YORK, A CORPORATION OF NEW YORK.

FOLDING TYPEWRITING-MACHINE.

1,387,362.

Specification of Letters Patent. Patented Aug. 9, 1921.

Application filed March 29, 1917. Serial No. 158,284.

To all whom it may concern:

Be it known that I, PHILIPPE DE CLAMECY, a citizen of the United States, and a resident of New York, county and State of New York, have invented certain new and useful Improvements in Folding Typewriting-Machines, of which the following is a full, clear, and exact description.

In the drawings, Figure 1 is a plan view 10 of the machine;

Fig. 2 a vertical sectional view thereof;

Fig. 3 a vertical sectional view of the platen carriage bed;

Fig. 4 a plan view thereof;

Fig. 5 a plan view of a portion of the platen carriage bed, with the platen carriage moved to its folding position;

Fig. 6 a similar view, showing the platen carriage moved at right angles to its operating position;

Fig. 7 a detail view showing the platen carriage placed on end and the carriage bed folded; and

Fig. 8 a detail horizontal sectional view 25 of the central carriage bed supporting post, showing the shift levers.

The main object of this invention is to provide a folding typewriting machine in which the keys are foldable upwardly and 30 toward the platen, suitably constructed joints being provided for the key levers.

Another object of the invention is to provide a removable platen carriage and a foldable sectional carriage bed whereby the 35 platen carriage may be placed vertically on end and the sections of the carriage bed folded upwardly to partly inclose the platen carriage.

There are other important objects and advantages of the invention which will appear 40 more fully hereinafter.

Referring to the various parts by numerals, 1 designates the base plate of the machine, 2 the bearing for the key levers, 45 said bearing being in form of a wire segmental in plan view; and 3 the key levers pivoted on said bearing. 4 designates the carriage bed which is formed in three sections, a central section 5, and two end sections 6 and 7, these latter sections being hinged to the ends of the central section and adapted to fold upwardly and inwardly. The bed is provided with tracks 8, in which is adapted to slide a supplemental bed plate 55 9. In this supplemental bed plate the carriage is adapted to slide transversely of the

machine. The supplemental bed is detachably secured in position by means of set screws or other devices.

Mounted on the central portion 5 of the carriage bed is a circular plate 11, said plate having a longitudinal flange 12 fitting the corresponding groove in the central part of the bed, as shown clearly in Figs. 2 and 4. The upper surface of the plate 11 is flush 65 with the upper surface of the central portion 5 of the carriage bed. This central plate 11 is grooved to receive the supplemental carriage bed 9; and is also formed with tracks 8^a, which correspond with the tracks 60 8 of the section 6. The section 7 of the main carriage bed is provided with tracks 8, as clearly shown in Fig. 4, and are for a purpose which will hereinafter appear. The supplemental carriage bed 9 is formed with 70 longitudinal extending ribs 9^b adapted to engage the tracks 8 and 8^a. This supplemental bed extends from end to end of the main bed and holds the tracks of the rotatable plate 11 in alinement with the tracks 75 8, as clearly illustrated in Fig. 4 of the drawings, and locks said plate against rotation. On the upper surface of the rotatable plate 11 are formed two hooks 13, said hooks being formed close to the section 7 of 80 85 the main bed and facing toward the section 6, said hooks being adapted to receive the outwardly extending lugs 11^a on the end of the supplemental bed. The lugs 11 are raised above the tracks 8 and are adapted to 90 move over said tracks as the supplemental bed is moved toward the right to bring the lugs 11 into engagement with the hooks 13, as shown clearly in Fig. 5.

The supplemental bed 9 is formed along 95 its longitudinal edges with inwardly extending tracks 14. Sliding on the supplemental bed is the platen carriage 15, the base plate 16 of said carriage being provided along its longitudinal edges with ribs 17 adapted to 100 fit in the tracks 14. The platen 18 is supported in standards 19 carried by the base plate 16. It will, of course, be understood that the base plate and the means for supporting the platen may be of any suitable 105 construction; and that the platen is to be provided with the usual paper guide 19^a, feed roll 20, and the usual disks or knobs 21, by means of which the platen may be rotated by hand. The carriage driving 110 drum 22 is mounted in the supplemental bed, and the driving cord 23 is connected to the

platen carriage, as indicated in dotted lines in Fig. 4. This driving drum and the connecting cord may be of any suitable construction, and may be arranged as desired 5 to secure the longitudinal advancement of the carriage for letter spacing.

When the supplemental carriage bed is in the position shown in Fig. 3, it is rigidly held by means of the set screws 10. The 10 platen carriage is then free to reciprocate upon said supplemental bed. When it is desired to fold the machine the screws 10 are loosened, and the supplemental bed is moved to the right to bring the lugs 11 into 15 engagement with the hooks 13. The ribs 9^b of the supplemental bed will then be free of the tracks 8^a on the central plate 11, and the supplemental bed with the platen carriage thereon may be swung upwardly and 20 placed on end substantially in the center of the plate 11, as shown in Fig. 7. The plate 11 may then be rotated on the central section 5 of the carriage bed, if desired, to bring the paper guide at the back or rear 25 of the machine. The two end sections of the carriage bed may then be folded upwardly toward the platen, as indicated in Fig. 7, thereby reducing the width of the machine.

The key levers are provided with an extension or supplemental member 3^a, said members being pivoted at their forward ends on the pivot wire 2; and the members 3 and 3^a are connected together by a knuckle joint 24, whereby upon the depression of the key 30 lever, the supplemental or extension member 3^a will be moved upwardly. The type bars 25 are pivoted at 26, and are formed with forwardly extending arms 27. The arm 27 of each type bar is provided with a pin 28 35 which enters a horizontal slot 29 in the member 3^a of a key lever. It is manifest that upon the depression of one of the keys its connected type bar will be thrown forwardly and downwardly to the platen. The 40 member 3^a of each key lever is maintained in its lower or normal position by means of a spring 30, said spring serving to throw the keys and type bars to their normal positions. The main portions of the key levers are 45 adapted to be swung upwardly and rearwardly to their folded position, as indicated by dotted lines in Fig. 2, thereby very materially reducing the length of the machine. Any suitable means may be employed to support 50 the type bars in their normal or at rest position. As shown in Fig. 2, this means consists of a plate 31 supporting a cushion, against which the type heads strike, and also supporting an upper protecting plate 32 55 which extends rearwardly over the type heads when said heads are in their normal at rest position against the cushion.

The platen carriage 16 is provided along its forward edge with a vertically arranged 60 ratchet rack 33, said rack facing toward the

front of the machine. Mounted upon a rigid support 34 is an escapement dog 35. This dog is provided with two pawls or detents, which are adapted to engage the teeth of the rack, as clearly shown in Fig. 4. Connected to the escapement dog is an operating arm 36 which is connected to the universal bar 37. The universal bar is pivoted in a standard 38 mounted on the base 1 of the machine, and extends forwardly and overlies the members 3^a of the key levers. As shown in Fig. 1, the universal bar is segmental in plan view, and is arranged to be lifted by the depression of any one of the character keys, and by the space key, to be 70 75 80 85 90 95 100 105 110 115 120 125 130 hereinafter described. It is manifest that by lifting the forward portion of the universal bar the arm 36 is moved rearwardly, thereby operating the escapement dog in the usual manner to permit the carriage to be moved one step for letter spacing. It will, of course, be understood that any suitable form of escapement dog, or escapement device, to be operated by the universal bar, may be substituted for the escapement dog shown in the drawings, said dog being shown merely by way of illustration.

The base plate 1 carries an upwardly extending cylindrical standard 39, whose vertical axis is in vertical alinement with the center of the rotatable plate 11. The central portion 5 of the carriage bed is formed with a depending tubular hub or socket 40, which is adapted to receive the cylindrical standard on the base plate, so that the bed plate 100 may be raised and lowered on the standard 39. Secured to the base plate are four upwardly extending sockets 41; and depending from the central portion 5 of the bed plate are corresponding guide pins 42, which fit and slide within said sockets. These pins and sockets maintain the carriage bed in its proper position on the base plate, while at the same time permitting vertical movement of said bed plate for the platen shift, as hereinafter described. Pivotaly mounted at the sides of the keyboard are case shift levers 43 and 44, said levers being pivoted at different points, in order to give variable shift movement to the carriage bed. Each of these shift levers is provided at its rear end with a yoke 45, which fits within a groove in the socket 40, whereby upon the depression of either shift lever the carriage bed will be raised. By providing the double shift mechanism for the carriage a three-character type head, as shown in the drawings, may be used.

Secured to the under side of the central portion of the carriage bed is a downwardly and forwardly extending plate 46. Mounted on said plate near its forward end are two conical ribbon guiding rollers 47, said rollers being suitably mounted and one of them being provided with a ratchet 48. Over 130

these rollers and through a ribbon guide 49 is passed an endless ribbon 50. The ribbon guide 49 maintains the ribbon at the printing point, and said guide is pivoted at 51 to the upper end of a rigid bar 52, this latter being supported on the plate 46, as clearly shown in Fig. 2. A suitable light spring is provided at the pivot 51 to maintain the upper part of the ribbon guide in its operative position close to the platen. Connected to the universal bar and vibrated vertically by it is a pawl 53, which is adapted to engage the ratchet 48 on one of the ribbon guiding rollers 47. Below each of the ribbon guiding rollers is an inking pad 54 so that the ribbon will be freshly inked as it passes between the guiding rollers and the inking pads.

The purpose of hinging the ribbon guide at 51 is to permit it to be swung forwardly out of the way of the platen when it is desired to move the platen to its vertical folded position.

The usual space key 55 is provided, said space key being hinged in a manner similar to the hinges of the character keys; and the rear ends of the space key levers project under the universal bar so that the said bar may be operated by the space key.

It is manifest from the foregoing, that a typewriting machine constructed as herein described, may be folded into a very small and compact package, suitable for transportation or for storage. The machine will not only be reduced in length from front to rear, but will be materially reduced in width, and when folded will form a package having its greatest dimension vertical.

What I claim is:—

1. In a typewriting machine, the combination of a carriage support, a platen carriage mounted thereon, means whereby the platen carriage may be folded relatively to the carriage support when the carriage is moved to one end of the support, and means whereby said support may be collapsed.

2. In a typewriting machine the combination of a main sectional foldable carriage bed, a supplemental bed mounted thereon, a platen carriage mounted on said supplemental bed and movable transversely thereof, a platen mounted on the carriage, and means whereby the platen carriage and supplemental bed may be folded bodily relatively to the main bed and the sections of the main bed folded relatively to each other.

3. In a typewriting machine, the combination of a sectional collapsible carriage bed, a platen carriage mounted thereon, and detachable therefrom to permit the bed to be collapsed.

4. In a typewriting machine, the combination of a sectional carriage bed, a supplemental carriage bed connected thereto and adapted to hold the sectional bed in its op-

erative position, a platen carriage mounted on said supplemental bed, and means to free the supplemental bed from the sectional bed to permit the said sectional bed to be folded.

5. In a typewriting machine, the combination of a base plate, a sectional carriage bed mounted thereon, a platen carriage mounted on and detachable from said sectional bed, and a case shift connected to said sectional bed and adapted to raise said bed for the printing of different case characters.

6. In a typewriting machine, the combination of a carriage bed comprising a central portion and two end portions pivoted thereto and adapted to be folded upwardly and inwardly, a supplemental carriage bed adapted to be secured to the sectional bed and to hold it in its extended operative position, a platen carriage mounted on said supplemental bed, means to free the supplemental bed from the sectional bed to permit said supplemental bed and the platen carriage to be placed on end over the central section of the supplemental bed and to permit the end sections of the carriage bed to be folded upwardly and inwardly.

7. In a typewriting machine, the combination of a carriage bed comprising a central portion and two end portions hinged thereto and adapted to be folded upwardly and inwardly, a rotatable plate mounted in the central section, a supplemental bed connected to the three sections of the carriage bed and adapted to hold all of said sections in their operative positions, means to free the supplemental bed from the carriage bed, and a platen carriage mounted on said supplemental bed.

8. In a typewriting machine, the combination of a carriage bed, comprising a central portion and two end portions hinged thereto and adapted to be folded upwardly and inwardly, a rotatable plate mounted in the central section, a supplemental bed connected to the three sections of the carriage bed and adapted to hold all of said sections in their operative positions, means to free the supplemental bed from the carriage bed, a platen carriage mounted on said supplemental bed, and a case shift connected to the carriage bed and adapted to move it vertically for the printing of different case characters.

9. In a typewriting machine, the combination of a foldable sectional carriage bed, a platen mounted thereon and foldable relatively thereto, type bars, keys and key levers therefor, the said key levers being adapted to be folded upwardly and rearwardly.

10. In a typewriting machine, the combination of a sectional foldable carriage bed having end sections adapted to be folded upwardly and inwardly, a platen carriage mounted on said bed and foldable relatively

- thereto, type bars, and key levers pivoted to fold upwardly and rearwardly.
11. In a typewriting machine, the combination of a support, a sectional foldable carriage bed having a central section mounted on said support, and end sections adapted to be folded upwardly and inwardly, a platen carriage mounted on said bed and foldable to a vertical position over the central section of the bed, type bars mounted on said support, and key levers pivotally held to said support and foldable upwardly and rearwardly relatively thereto. 10
12. In a typewriting machine the combination of a support, a sectional foldable carriage bed having a central section held to said support and end sections adapted to be folded upwardly and inwardly, a platen carriage mounted on said bed and foldable to a vertical position over the central section thereof, type bars mounted on said support, two-part key levers pivotally mounted on said support intermediate their ends and operatively connected with the type bars, and foldable connections between the parts of said key levers whereby the forward key-carrying parts thereof may be folded upwardly and rearwardly to vertical positions. 20
13. In a compactible typewriting machine the combination of a carriage bed having relatively foldable parts, a platen carriage mounted thereon, means whereby the platen may be placed on end over the center of the bed, and means whereby the end portions of the bed may be folded upwardly at opposite sides of the platen when the platen is placed on end. 30
14. In a compactible typewriting machine the combination of a frame, a platen carriage support mounted on the frame, a carriage mounted on said support to travel transversely of the frame during its letter-spacing movement, means whereby portions of said support may be folded to reduce its length, and means whereby the carriage may be folded to a compact position within the vertical planes of the ends of the folded support. 40
15. In a compactible typewriting machine the combination of a base the length and width of which are materially less than the normal length and width of the machine, type bars mounted on said base, a keyboard mounted on the base and having its forward portion projecting beyond the forward edge of the base, a platen support of greater length than the width of the base mounted on said base, a platen mounted on said support, and means whereby said keyboard and the platen and platen support may be folded relatively to the base from their normal operative positions overhanging the edges of the base to compact positions above the base and within the vertical planes of the edges of said base. 50
16. A typewriting machine, comprising a collapsible carriage bed, and an upwardly and rearwardly foldable keyboard whereby the machine may be reduced in width and length in its inoperative position. 70
17. A typewriting machine, comprising a collapsible carriage bed, a detachable platen carriage, and an upwardly and rearwardly foldable keyboard, whereby the machine may be reduced in width and length in its inoperative position. 75
18. A compactible typewriter, comprising a carriage bed adapted to be collapsed to reduce the width of the machine, a platen carriage mounted on said bed, a keyboard foldable upwardly and rearwardly to reduce the length of the machine, whereby the said machine may be reduced in width and length in its compact position. 80
19. A typewriting machine, comprising a carriage bed adapted to be collapsed to reduce the width of the machine, and a detachable platen mounted thereon. 85
20. A typewriting machine comprising a collapsible carriage bed, and a platen carriage mounted on said bed and foldable to a vertical position, whereby the width of the machine may be reduced. 90
21. A compactible typewriter, comprising a carriage bed adapted to be collapsed to reduce the width of the machine, a platen carriage mounted on said bed and movable to a compact position when the bed is collapsed, a keyboard foldable to reduce the length of the machine, whereby the said machine may be reduced in width and length in its compact position. 95
22. In a typewriting machine, the combination of a bed, a platen carriage, and means for permitting the platen carriage to be placed on end directly over the center of the bed. 105
23. In a compactible typewriting machine the combination of a relatively small base, a collapsible carriage bed having its ends normally extending beyond the sides of the base, a platen carriage of greater length than the width of the base mounted on said bed, type bars mounted on the base, key levers mounted on the base operatively connected with the type bars and having their key-carrying portions extending forwardly beyond the front edge of the base, and means whereby the carriage and the projecting end portions of the carriage bed and key levers may be folded to compact positions over the base to reduce the length and width of the machine. 110
24. A typewriting machine having a compactible carriage bed comprising relatively foldable parts, and a platen carriage adapted to travel upon said compactible bed and foldable with a part thereof to reduce the width of the machine. 120
25. A typewriting machine having platen 130

supporting means embodying a compactible carriage bed comprising relatively foldable parts and a platen carriage adapted to travel upon said bed and foldable with a 5 part thereof to reduce the width of the machine, type bars, and a key action having key levers extending radially from the type bars, the forward parts of said levers being foldable upwardly and rearwardly 10 along converging lines into compact relation with the type bars to reduce the length and width of the key action.

26. A typewriting machine having a platen carriage and a carriage bed foldable 15 to reduce the width of the machine, and a keyboard foldable to reduce the length and width thereof.

27. A compactible typewriting machine having a platen, supporting means for the 20 platen, means whereby the platen and its supporting means may be shifted to positions in which the width of the machine is reduced, type bars, a key-action for operating the type bars, and means whereby the 25 length and width of the key action may be reduced.

28. In a typewriting machine, the combination of a relatively narrow frame, compactible platen supporting means normally 30 extending beyond the sides of the frame and collapsible to reduce the width of the machine, and a keyboard normally wider than the frame and contractible transversely to reduce the width of the keyboard 35 when not in use.

29. A typewriting machine having a platen, a type basket, means whereby the 40 platen may be shifted bodily from a normal operative position to an inoperative position within the planes of the sides of the type basket to reduce the width of the machine, and a key action adapted to be compacted to reduce the length and width thereof.

30. In a typewriting machine the combination of a carriage bed comprising a central portion and two end portions hinged thereto and adapted to be folded upwardly and inwardly, a rotatable plate mounted in 45 the central section, a supplemental bed connected to the three sections of the carriage bed and adapted to hold all of said sections in their operative positions, means whereby the supplemental bed may be freed from 50

the carriage bed and connected with the rotatable plate to fold upwardly to a vertical position above said plate and to be rotated with said plate relatively to the carriage bed when in its vertical position, and a platen carriage mounted on said supplemental bed. 55

31. In a typewriting machine, the combination of a relatively short and narrow frame, platen supporting means normally overhanging the sides of the frame and collapsible to reduce the width of the machine, type carriers mounted on the frame, and a compactible key action embodying two-part key levers having the key-carrying parts thereof shiftable to reduce the width of the 65 keyboard and to place the compacted keyboard closer to the type carriers to reduce the length of the machine from front to rear. 70

32. In a compactible typewriting machine, a compactible type action comprising 75 type carriers, and two-part key levers operatively connected to actuate the type carriers, the key carrying parts of said levers being shiftable relatively to the type carriers to reduce the width and length of the 80 machine as a whole.

33. In a compactible typewriting machine, a compactible type bar action comprising type bars, and two-part key levers operatively connected to actuate the type 85 bars, the key-carrying parts of said levers being foldable upwardly and rearwardly relatively to the type bars along radial lines to reduce the length and width of the machine as a whole. 90

34. In a typewriting machine, the combination of a relatively narrow frame, platen supporting means normally extending beyond the sides of the frame and collapsible to reduce the width of the machine, a platen 95 shiftable relatively to the supporting means to a compact position overlying the frame, type carriers mounted on the frame, and a keyboard normally wider than the frame, the keys of said keyboard being shiftable 100 to contract the keyboard transversely and to place the contracted keyboard close to the type carriers.

This specification signed and witnessed this 13th day of December A. D. 1916.

PHILIPPE DE CLAMECY.

Witness:

E. A. KING.
